UNITED STATES PATENT OFFICE.

JOHN S. HULL, OF CINCINNATI, OHIO.

IMPROVEMENT IN LAMPS.

Specification forming part of Letters Patent No. 124,823, dated March 19, 1872; antedated March 9, 1872.

SPECIFICATION.

I, JOHN S. HULL, of Cincinnati, in the county of Hamilton and State of Ohio, have invented certain new and useful Improvements in Fluid-Lamps, of which the following is a specification:

Nature and Objects of the Invention.

My invention relates to that class of vapor lamp-burners which are fed by capillary attraction; and consists in the application of appropriate means for the isolation of heat from the fluid in the reservoir, all of which will be fully understood by reference to the drawing and following general description.

Description of the Accompanying Drawing.

Figure 1 is a vertical section through the center of the lamp and burner embodying my invention.

General Description.

A is the base of the lamp below the reservoir. C is a safety-wick chamber through the center of the reservoir B, and is made of wire-gauze or other suitable material. H is the burner, the holes *h h* of which for the egress of the vapor are made conical with the cone, increasing outward, and are arranged between the flanges *c* and *l*. The office of the upper flange *c* is to receive heat from the flame to be transmitted to the fluid. The lower flange *l* is particularly designed to protect the jets of flame from currents of wind or air, which otherwise would extinguish the light, and at the same time serves as a heater. I make the flanges in one piece with the burner, and prefer to have the flame jets close to the lower one, in which, immediately under the jets, I make a groove, which allows a free circulation of air; keeps the holes free from obstruction; and dispenses with the necessity of air-holes through the flange. *m* is a sleeve or thimble, made in one piece with or attached to the cap or burner *H*. *n* is the wick-pipe leading from the reservoir to the burner, the upper end of which is made with a thread to fit the thread

of the sleeve *m*, as shown. By means of these male and female threads the burner may be elevated or depressed at pleasure. When it is desired to diminish the volume of light and flame the cap should be elevated, and when it is desired to extinguish the light and immediately stop the flow of vapor it should be screwed down tight. *R* is the isolation-chamber, which is made with a flange, *S*, at its lower end for the purpose of increasing its strength and fitting tightly upon the collar of the lamp, into which it screws. At the top of the chamber there is a ring, *P*, fitted to the wick-pipe, which projects in the form of a flange. Immediately against this ring I place a paper or leather washer, or both, as shown at *Q*. The chamber *R* is fitted tightly up against the washer, and the space between the wick-tube and the wall of the chamber *R* is packed with cork to the depth of about half an inch. The filling is then continued with plaster-Paris or other suitable cement to within about half an inch of the bottom, when the packing is completed with cork. Under the lower side of the flange *S* is placed a paper or leather washer, or both, as shown at *S'*. That portion of the wick-pipe *m*, when made of brass, which is between the flanges *P* and *S* is severed and a piece of tin or other slow conductor of heat soldered in. The whole is kept tight and in place by a plate screwed on the lower end of the wick-pipe. This plate must not touch the sides of the surrounding metal.

Claim.

Having thus described my invention, what I claim as new, and desire to secure by Letters Patent, is—

In combination with the burner and wick-tube, the isolation-chamber, composed substantially of the part *R* and its filling of cork and plaster-Paris, and the washers *Q* and *S'*, arranged as herein shown and described.

JOHN S. HULL.
